ANCHORING PLUG

Filed March 18, 1929

Edwin James Whiffen.
INVENTOR.

UNITED STATES PATENT OFFICE

EDWIN JAMES WHIFFEN, OF MOUNT VERNON, NEW YORK

ANCHORING PLUG

Application filed March 18, 1929. Serial No. 348,049.

The invention relates to plugs, made from stranded fibrous material and a cement, used to form an anchorage for screws, nails, or the like when inserted in prepared holes 5 in stone, concrete, brick, glass, metal or other hard material.

Plugs of this general type have heretofore been tubular. The reason for this has been to provide a means of guiding the 10 screw and keeping it in the center of the plug. The present invention has no center hole. It is so made that the core is not so thoroly impregnated with cement as is the outer portion of the plug. A plug so made 15 guides and centers the screw equally as well as a tubular plug does.

Within certain limits the holding power of a fibre screw anchor is proportional to the amount of material in that anchor. 20 Therefore the present invention has greater holding power than the tubular forms of plugs made of the same kind of material compressed to the same degree, because the volume of a solid cylindrical form is greater 25 than that of any possible tubular form of the same outside dimensions.

Besides greater holding power, another advantage of the present invention is the ease with which a means of lubricating the 30 screw may be incorporated. By impregnating the core of the plug with a lubricant as the plug is being made, it is possible to have a plug, the lubricant in which will not dry up nor shake out during the transportation and handling of the plug after it is 35 made and before it is used as a screw anchor.

Another advantage of the present invention is the ease and economy of manufacture. 40 This is due to the fact that no mandrel is required. In the manufacture of tubular plugs a mandrel is used to form the center hole. After the product is shaped into a tubular form it is drawn thru a 45 drying oven which sets the cement. The mandrel must be long enough to insure that the product has set to the required tubular form before it reaches the end of the mandrel. This means that the mandrel must 50 extend well into, or thru, the drying oven.

It is this part of the mandrel located in the oven that causes tubular plugs to be more difficult and expensive to manufacture than the present invention. As the product passes thru the oven some of the cement 55 adheres to the mandrel and is baked on. The frictional drag due to the cement coating baked on the mandrel may become great enough to overcome the pulling power of the drawing-in rollers. In this case the 60 product stands still in the oven and a "burn-up" is sure to follow if the machine is not immediately tended and the mandrel withdrawn and cleaned. This limits the number 65 of machines one operator can tend, making the labor cost greater than in the manufacture of the present invention, in which no mandrel is required. If there is a "burn-up", it is necessary to clean the mandrel and re-set-up the machine, all of which 70 adds to the labor cost besides stopping production. It sometimes happens that the coating of cement on the mandrel splits the product instead of stopping it. The split 75 plugs so made are thrown away as waste for they are even more fragile than the regular product.

Another advantage of the solid plug, the present invention, is that it is not so fragile as the tubular plug. It can stand contact 80 with heavy objects without becoming so crushed and broken as to be useless.

Still another advantage of the present invention is that solid plugs may be coated with shellac, varnish, or other material 85 without possibility of filling any center hole and thus destroying the screw-guiding properties. Such a coating gives an improved appearance to the plug and helps it resist moisture. In some cases such a coating increases the holding power of the plug. 90

In the accompanying drawing is illustrated one form of this invention. The drawing shows a plug in which the core A is surrounded by strands B parallel to the core. 95 It is also possible to make a plug with the outer strands B either laid spirally about core A or plaited about such core. If two or more layers of outer strands B are used 100 in making the plug such layers may be ar-

ranged in any combination desired, for example, a layer of parallel strands about the core in turn surrounded by plaited strands. In any case the strands B are joined to each other and to the core A by means of a cement. The core A may be of untreated fibrous material or the material may be impregnated with a lubricant. It is also possible to make plugs in which the outer strands B are joined to each other but not to the core A by means of a cement.

One method of making this invention is to draw off from a spool the fibrous material which forms the core, this material may be lubricant treated or not as may be desired. This core is then surrounded by other strands which have been drawn from spools and impregnated with a cement. The whole is drawn through a die to scrape off the excess cement and is then drawn through heated dies in a drying oven to dry and set the product. The purpose of the heated dies, besides helping dry the product, is to hold the product together until the setting of the cement has bound the product together. With some kinds of cement the heated dies are not necessary, merely running the product through the drying oven being sufficient to dry and set the product in the required form. After being drawn through the oven the product may be cut into plugs of the desired length by means of a cutter. Grooved rollers form a satisfactory means of drawing the product through to the cutter.

35 I claim:

1. A plug, made of stranded fibrous material and a cement, and having a solid core less firm than the outer portion.
2. A plug, made of stranded fibrous material and a cement, and having a solid core lubricant impregnated, said core being less firm than the outer portion.

EDWIN JAMES WHIFFEN.
